(57) **CLAIM**

The ornamental design for edging for materials as shown and described.

DESCRIPTION

FIG. 1 is a perspective view of edging for materials showing our new design;

FIG. 2 is a cross-sectional perspective view of the edging for materials, taken along lines 2-2 in FIG. 1;

FIG. 3 is a top plan view of the edging for materials shown in FIG. 1;

FIG. 4 is a front elevation view of the edging for materials shown in FIG. 1;

FIG. 5 is a rear elevation view of the edging for materials shown in FIG. 1;

FIG. 6 is a right side plan view of the edging for materials shown in FIG. 1; and,

FIG. 7 is a left side plan view of the edging for materials shown in FIG. 1.

The evenly spaced broken lines in FIGS. 1 through 7 represent portions of the edging for materials and form no part of the claimed design. The edging for materials is shown with a symbolic break in its length and width. The appear-
